Uniroyal, Inc., New York, N.Y.

Filed May 3, 1971, Ser. No. 139,996

Term of patent 14 years

Int. Cl. D12—15

U.S. Cl. D90—20

FIG. 2.

FIG. 5.

FIG. 3.

FIG. 4.

FIG. 1 is a perspective view of a pneumatic tire showing my new design, it being understood that the shaded tread and shaded buttress portions continue throughout the circumference of the tire, and that the buttress pattern is the same on both sides of the tire;

FIG. 2 is an enlarged, fragmentary plan view of the tread of FIG. 1;

FIG. 3 is an enlarged, fragmentary plan view of the butress of FIG. 1;

FIG. 4 is a fragmentary sectional view of the tread, taken substantially on the plane indicated by line 4-4 of FIG. 2; and

FIG. 5 is a fragmentary sectional view of the butress, taken substantially on the plane indicated by line 5-5 of FIG. 3.

The characteristic feature of my design resides in the tread and butress pattern extending from one sidewall of the tire to the other and shaded in FIG. 1.

I claim:

The ornamental design for a pneumatic tire, substantially as shown and described.
